US00D847124S

(12) **United States Design Patent** (10) **Patent No.:** **US D847,124 S**
(45) **Date of Patent:** **** Apr. 30, 2019**

(54) **EARPIECE**

(71) Applicant: **SureFire, LLC**, Fountain Valley, CA (US)

(72) Inventors: **Richard C. Smith**, Costa Mesa, CA (US); **Diann Y. Smith**, Costa Mesa, CA (US); **Alfredo Soria**, Corona, CA (US)

(73) Assignee: **SureFire, LLC**, Fountain Valley, CA (US)

(**) Term: **15 Years**

(21) Appl. No.: **29/594,279**

(22) Filed: **Feb. 16, 2017**

Related U.S. Application Data

(63) Continuation of application No. 29/541,896, filed on Oct. 8, 2015, now Pat. No. Des. 779,461.

(57) **CLAIM**

The ornamental design for an earpiece, as shown and described.

DESCRIPTION

FIG. 1 is a front right perspective view of an earpiece showing our new design;

FIG. 2 is a rear left perspective view thereof;

FIG. 3 is a left side elevational view thereof;

FIG. 4 is a right side elevational view thereof;

FIG. 5 is a front side elevational view thereof;

FIG. 6 is a rear side elevational view thereof;

FIG. 7 is a top plan view thereof;

FIG. 8 is a bottom plan view thereof;

FIG. 9 is a cross-sectional view thereof taken at line 9-9 of FIG. 3; and

FIG. 10 is a cross-sectional view thereof taken at line 10-10 of FIG. 4.

FIG. 11 is a front right perspective view of an example audio device for an earpiece shown in broken lines;

FIG. 12 is a front left perspective view thereof;

FIG. 13 is a rear right perspective view thereof; and

FIG. 14 is a rear left perspective view thereof.

FIG. 15 is a front right perspective view of the earpiece with the example audio device attached thereto, drawn in broken lines;

FIG. 16 is a front left perspective view thereof;

FIG. 17 is a rear right perspective view thereof; and,

FIG. 18 is a rear left perspective view thereof.

The broken lines in the drawings illustrate environmental features and form no part of the claimed design.

1 Claim, 18 Drawing Sheets
